UNITED STATES PATENT OFFICE.

JOHN M. KINCADE, OF SPRINGFIELD, MASSACHUSETTS.

CEMETERY-CAR.

1,266,601.

Specification of Letters Patent. Patented May 21, 1918.

Application filed November 2, 1917. Serial No. 199,830.

To all whom it may concern:

Be it known that I, JOHN M. KINCADE, a citizen of the United States, residing at Springfield, in the county of Clark and State of Ohio, have invented certain new and useful Improvements in Cemetery-Cars, of which the following is a specification, reference being had therein to the accompanying drawing.

This invention relates to improvements in cemetery cars and has for its object to provide such a car useful in connection with the digging of graves or vaults in a cemetery and adapted to contain the dirt removed from such a grave or vault and to replace the dirt inside the grave at a single operation.

In the ordinary method of grave digging the dirt removed from the grave is simply piled by the side thereof and is, of course, very unsightly. It is a frequent custom to cover the dirt with a canvas or some other piece of cloth so as to hide it from the view of the funeral party. After the funeral ceremony takes place the dirt is ordinarily shoveled back into the grave after the party has left the vicinity.

This invention contemplates the employment of a car having a dumping or removable bottom and provided with sides and a top which may be independently adjusted. It is moved near the location where a grave is to be dug and the dirt removed from the grave instead of being placed on the ground is thrown into the car body. Then the car may be removed from the location of the grave if desired and the replacement of the top prevents rain or snow from affecting the dirt held in the car body. After a funeral service the car may be moved directly over the opened grave and the dirt held therein dumped into the grave at a single operation. This operation of returning the dirt to the grave may in fact take place in the presence of the funeral party if that is desired, as it requires only a moment to bring the car above the grave and to dump the dirt therefrom.

In the accompanying drawings, Figure 1 shows a plan view of a cemetery car in accordance with this invention, the car being shown as placed beside an open grave ready to be moved thereover so as to replace the dirt;

Fig. 2 shows an end view of one form of such a car with road wheels attached there-

to so that it may be moved throughout the cemetery;

Fig. 3 is a similar view to Fig. 2 but showing a set of track wheels attached to the car, 60 these wheels moving on tracks placed beside the open grave, as indicated in the figure;

Fig. 4 is a detail showing a different form of dumping bottom;

Fig. 5 is a side view showing a further 65 modified form of bottom and indicating the sides of the car as pivoted so that they may turn back;

Figs. 6 and 7 show an additional modified form of bottom, the bottom of Fig. 6 being 70 shown in position to retain the dirt while in Fig. 7 the car is shown as over an open grave with the bottom depressed to permit dumping of the dirt.

Referring to Fig. 1 the car is shown as 75 having sides 1 through which axles 2 run, these axles supporting road wheels 3. At right angles to the axles 2 are axles for track wheels 5, these track wheels being provided with flanges so that they may run on tracks 6. As shown these tracks are on opposite sides of a grave 7 and the tracks may be held the proper distance apart by any form of tie 8. A tongue 9 may be attached to the front axle 2 of the car so as to permit the attachment of horses to pull the car about the cemetery. The road wheels 3 extend to points below the track wheels 5 and thus the wheels 5 do not touch the tracks 6 until the wheels 3 are removed. This may be, of 90 course, done by jacking the axles 2 and then the wheels may be readily removed. Lowering the jacks permits the track wheels 5 to rest on the track 6 and support the weight of the car. 95

In the figures the car body is shown as provided with a top comprising pivoted portions 9 which may be turned back in the position shown in Fig. 3 or may be elevated to a perpendicular, as also shown in the same 100 figure. It will be understood that the portion 9 of the top which is nearest the grave 7 will be lowered, as shown at the right of Fig. 3, so as to permit the dirt being thrown thereover, while the portion 9 of the top at 105 the left of this figure is maintained perpendicular as by a hook 10, so as to prevent dirt being thrown entirely over the car and landing on the ground at the opposite side. Fig. 5 also shows sides or ends of the car as 110 being pivoted, the pivoted portions 11 being adapted to be raised to a vertical position,

as shown, or being turned downwardly so as to permit the dirt from the grave to be thrown readily into the car from any desired direction. It will be understood that the inequalities in the ground usually found in cemeteries render the feature of being able to fill the car with dirt from any direction of great advantage.

The figures show various forms of car bottom which may be readily drawn so as to permit dumping of the dirt held therein. Fig. 5 shows a sliding bottom 12 in two portions. Fig. 2 shows a pivoted bottom which may be elevated or depressed by a cord 13 wound on a windlass 14 controlled by a crank 15 and held against movement by a pawl 16. In the form of Fig. 4 the bottom is centrally pivoted on a shaft 17 controlled by a crank 18. In this form the portion 19 of the bottom is rigid with the shaft 17, while the portion 20 is pivoted thereto and rests on a frame piece 21 of the car body. The portion 19 extends from the shaft 17 through a smaller distance than the portion 20 and therefore will pass entirely inside the frame piece 21.

In the form of Fig. 6 the bottom is composed of two sections, each section having parts 22 and 23 pivoted together, the part 22 having a flange 24 overlapping the part 23. This form of bottom may be operated by the windlass construction shown in Fig. 2 and is indicated in Fig. 7 as directly over the grave and with the bottom depressed so as to permit the movement of the dirt.

The operation of the cemetery car shown in the drawings may be briefly recapitulated as follows: When a grave is to be dug the car is moved adjacent thereto on its road wheels 3, a position being chosen such that the dirt may be readily thrown into the car. The top of the car is adjusted, as shown in Fig. 3 and the end most distant from the grave may be elevated and the side or end nearest the grave depressed so as to permit the dirt to be readily thrown into the car body. When the grave has been completely dug the car may be moved entirely away from the vicinity if desired until the time for the funeral service. Then it is returned to the vicinity of the grave, the tracks 6 properly adjusted and the road wheels then taken off the car and the track wheels engaged with the tracks 6. Then after the conclusion of the funeral ceremony the car may be pushed directly over the grave, as indicated in Fig. 7, and the dirt immediately deposited therein. The use of the road wheels 3 permits the car to be readily moved throughout the cemetery, but if the car is to remain in the vicinity of the grave the road wheels may be detached before the grave is dug and the car permitted to remain in the same position of Fig. 1 until the funeral ceremony takes place.

As a matter of further improvement Fig. 3 shows a post 31 detachably mounted on the car, this post having a horizontal extension from which may be suspended an awning 32 directly over the grave 7 so as to protect it from the direct rays of the sun, rain or snow.

While I have shown and described one embodiment of the invention, it will be understood that the same has been chosen for purposes of illustration only, and that I do not desire to be limited to the details of construction shown and described, for obvious modifications will occur to a person skilled in the art.

Having thus fully described my invention, what I claim as new and desire to secure by Letters Patent, is:—

1. In a cemetery car, the combination, with pairs of axles at right angles to each other, of track wheels carried by one pair of axles, road wheels carried by the other pair of axles, said road wheels extending to points lower than said track wheels, and a car body under which said axles are mounted, said body having a dumping bottom, pivoted sides and a pivoted top.

2. In a cemetery car, the combination, with pairs of axles at right angles to each other, of track wheels mounted on one pair of said axles, road wheels mounted on the other pair of axles and extending to points lower than said track wheels, a car body under which all said axles are mounted, said body having a dumping bottom and sides slanting upwardly and outwardly from said bottom.

3. In a cemetery car, the combination, with a car having road wheels and track wheels, the road wheels extending to points lower than said track wheels, of a body mounted on said wheels and having a dumping bottom, with means, such as a ratchet for dumping said bottom, of rails, adapted to be placed beside an open grave, on which said track wheels may run so as to permit movement of the car body over the open grave.

4. In a cemetery car, the combination, with a car having track wheels, and a body supported by said wheels, said body having a dumping bottom, and pivoted top and sides, of rails, adapted to be placed beside an open grave, on which said track wheels may run, so as to permit movement of said car body over an open grave, and dumping of dirt directly from the car into the grave.

5. In a cemetery car, the combination, with a car having track wheels, and a body supported by said wheels, said body having a pivoted bottom, with means such as a ratchet for rotating said bottom, said sides having pivoted portions which may be separately turned downward, and a pivoted top which may be held upright by a hook, of

rails, on which said wheels may run so as to carry the car body over an open grave and permit dumping dirt directly from the car body into the open grave.

5 6. In a cemetery car, the combination, with a car having track wheels, and a body supported by said wheels, said body having sides with pivoted portions which may be separately turned downward, and a pivoted

top which may be held upright by a hook, 10 of rails, on which said car wheels may run so as to carry the car body adjacent a grave site, whereby dirt taken from a grave may be thrown over a downwardly turned side of the car body into the car. 15

In testimony whereof I affix my signature.

JOHN M. KINCADE.

Copies of this patent may be obtained for five cents each, by addressing the "Commissioner of Patents, Washington, D. C."

It is hereby certified that the residence of the patentee in Letters Patent No. 1,266,601, granted May 21, 1918, upon the application of John M. Kincade, for an improvement in "Cemetery-Cars," was erroneously written and printed as "Springfield, Massachusetts," whereas said residence should have been written and printed as *Springfield, Ohio*; and that the said Letters Patent should be read with this correction therein that the same may conform to the record of the case in the Patent Office.

Signed and sealed this 29th day of October, A. D., 1918.

[SEAL.]

R. F. WHITEHEAD,

Acting Commissioner of Patents.

Cl. 105—14.
